Inventor
H. M. Hutchinson

By Clarence A. O'Brien

Attorney

Patented May 10, 1927.

UNITED STATES PATENT OFFICE.

HOWARD M. HUTCHINSON, OF BROCK, NEBRASKA.

WRENCH.

Application filed December 8, 1925. Serial No. 74,067.

This invention relates to wrenches of the spanner type, and the primary object thereof is to provide such a tool wherein the head is disposed at a plurality of angles with respect to the handle in order that nuts in inaccessible and close places may be readily applied or removed.

A further object of the invention is to provide means whereby the handle may be ratcheted with respect to the head in order that nuts may be applied or removed when it is impossible to use a wrench unless but relatively slight movement of the handle is permissible.

15 A further and important object is to provide a wrench of this character wherein heads of various sizes and shapes may be associated with the handle for use in conjunction with nuts of various sizes and shapes.

20 With the foregoing and other objects in view as the nature of the invention will be better understood, the same comprises the novel form, combination and arrangement of parts hereinafter more fully described and 25 shown in the accompanying drawings and claimed.

In the drawings wherein like reference characters indicate corresponding parts throughout the several views:

30 Figure 1 is a side elevation of my improved wrench.

Fig. 2 is a similar view, one wall of the handle being broken away at its forward end for more clearly disclosing the ratchet mechanism between the handle and the head,

35 and

Fig. 3 is a detail section taken substantially upon the line 3—3 of Fig. 2.

Now having particular reference to the drawing, my wrench is shown as comprising a handle 5 and a jaw 6.

The handle 5, which is of suitable material, is preferably flat shaped and consists of two parallel members 7 and 8 of similar shape that are disposed in face to face relation and so secured through the medium of rivets or the like 9.

The forward ends of the members comprising the handle 5 are of general C formation as shown at 10 in Fig. 1, the material forming the handle members being cut away at opposed surfaces of the C-shaped ends 10 for receiving a similarly shaped rib 11 of the jaw 6.

55 At opposite sides of the rib 11 of said jaw grooves 12 are provided which open

at one end of the jaw and terminate at their opposite ends inwardly of the opposite end of the jaw as more clearly shown in Fig. 2.

At the edges of the C-shaped ends of the members forming the handle 5, inwardly directed flanges 13 are provided of a shape complementary to the shape of the groove 12 for engaging within said grooves in order that the jaw 6 will be properly guided in its turning movement within the end of the handle.

Directly adjacent the jaw carrying end of the handle members the contact faces of the members are cut away to provide a pocket 14 for a plate-like dog 15 which is pivoted at 16 within said pocket. At one side of the pivot 16 one edge of the dog carries a pin 17 that extends outwardly through an opening 18 formed in the adjacent edge 75 of the handle 5 in order that said dog may be swung in one direction on its pivot.

Arranged at one end between the members forming the handle is a leaf spring 19, the opposite end of which engages upon the edge of the dog opposite from that carrying the pin 17 in order that the dog will be normally maintained in the position as shown in Fig. 2, in which position, the nose 20 which is forwardly of the pivot pin 16 will engage ratchet teeth 21 upon the inner edge of the rib 11 of the said jaw 6.

From the foregoing description it will be obvious that a turning of the handle 5 in one direction will occasion the turning of the jaw 6 in the similar direction but in view of the ratchet connection between the members, the handle may be moved backwardly without effecting a consequent movement of the jaw for thus enabling the jaw to be moved to the limit of its degree through relatively short movements of the handle member with the end in view of allowing the nuts in inaccessible places to be readily applied or removed.

Even though I have herein shown and described certain detail structural elements, it is nevertheless to be understood that I do not desire to be limited to the specific construction of the elements insomuch as in future practice of the invention, minor changes may be made therein without departing from the spirit and scope of the appended claim.

Having thus described my invention, what I claim as new and desire to secure by Letters Patent is:—

In a wrench of the class described, a handle, a substantially C-shaped jaw, a C-shaped rib formed on the back of the jaw, said rib having channels formed in the opposed faces thereof extending from one end of the C-shaped jaw to a point adjacent the other end, there being ratchet teeth formed in the edge of the rib, said handle including a pair of flat elongated members secured together in face-to-face relation, the inner ends of the members being of C-shape formation and being cut away at the opposite surfaces for receiving the C-shaped rib formed on the jaw, the inner ends of the members comprising the handle having inwardly directed flanges formed thereon for

engagement within the respective channels formed in the opposed faces of the rib, said rib being disposed within the cut out portion of the complementary members comprising a handle, said handle being formed with a pocket between the members at a point adjacent the inner end thereof, a dog pivotally arranged within the pocket and having one end in normal engagement with the ratchet teeth, and a pin carried by the dog and extending laterally through one of the side edges of the handle to facilitate the disengagement of the dog from the teeth. 20 25

In testimony whereof I affix my signature.

HOWARD M. HUTCHINSON.
